Fred Kuehne, Jr., Mattoon, Ill.

Application July 24, 1952, Serial No. 20,742

Term of patent 14 years

(Cl. D33—14)

To all whom it may concern:

Be it known that I, Fred Kuehne, Jr., a citizen of the United States, residing at Mattoon, in the county of Coles and State of Illinois, have invented a new, original, and ornamental Design for Table, of which the following is a specification, reference being had to the accompanying drawing, forming part thereof.

Figs. 2, 3 and 4 are front, side and top views respectively of the table leg element thereof.

The dominant features of my design reside in the portions shown in full lines.

I claim:

The ornamental design for a table, as shown and described.

FRED KUEHNE, JR.
